UNITED STATES PATENT OFFICE

HARRY A. EATHERTON, OF FINDLAY, OHIO, ASSIGNOR TO PORCELAIN PRODUCTS, INC.,
OF FINDLAY, OHIO, A CORPORATION OF DELAWARE

PROTECTIVE DEVICE

Application filed November 22, 1927. Serial No. 235,055.

The present invention has reference to protective devices for electrical circuits and deals more particularly with that class of protective devices which is utilized to protect radio circuits and the like from the effects of high voltages whether produced by lightning, adjacent power lines, or static discharge.

Stated more specifically this present invention relates to a type of protective device having two electrodes separated by a gap of such a character that abnormal voltages will cause a discharge from one electrode to the other, one of the electrodes being grounded.

It is an object of the present invention to produce a protective device of the nature described which will function to protect the circuit with which it is used from the effect of abnormal voltages.

It is a further object of the present invention to provide a protective device of the nature described which is specially adapted for use in connection with the protection of radio apparatus and circuits.

It is a still further object of the present invention to provide a method of manufacture for protective devices of this nature by means of which the protective devices can be quickly and easily assembled and the proper gap formed between the electrodes.

It is a still further object of the present invention to provide a method of manufacture of a protective device of the nature described in which the proper relationship of the electrodes is obtained through the subsequent change of temperature of some of the materials used or applied in a heated state.

The present invention will be better understood by reference to the accompanying drawings which show for the purpose of illustration, various forms of the protective device and its method of manufacture.

Referring to the drawings,

Fig. 1 is a view of a preferred embodiment of the protective device;

Fig. 2 is a section of the device shown in Fig. 1;

Fig. 3 is a view partially in section of a modified form of the device, and

Fig. 4 is a partial sectional view illustrating

ing a method of assembling the preferred embodiment.

Referring now to the figures, and more particularly to Figs. 1 and 2, the embodiment herein shown comprises insulating receptacle 1 constructed of suitable insulating material such as glazed porcelain. This receptacle is constructed with an upper truncated conical portion 2, the lower end of which extends out and beyond a plurality of concentric corrugations 3 and 4, the purpose of this construction being that of providing as high a resistance path as possible between the upper and lower portions of the insulating receptacle under all weather conditions. A central axial tubular opening 5 extends through the receptacle.

A pair of electrodes 6 and 7 of brass or other suitable material are mounted within the opening 5 with their inner ends closely adjacent but spaced from each other as shown so as to form a gap of such a nature as to permit abnormal voltages to discharge from one electrode to another. For the purpose of making clear the structure, this gap is shown in the drawings, but in the actual structure the gap is microscopic in character. While not essential to the present invention the electrodes 6 and 7 are provided in the described embodiment with enlarged heads or ends 8 and 9 between which the gap is formed.

The outer ends of the electrodes 6 and 7 are threaded and provided with nuts 10, 12, for the purpose of incorporating the protective device into the electrical circuits with which it is associated. For instance a ground wire may be clamped between the nuts 12 while an antenna and associated lead-in may be clamped between the top nuts 10 when the protective device is used in connection with radio circuits.

In order to suitably hold the electrodes 6 and 7 in the desired position with respect to each other and with respect to the receptacle 1 the central opening 5 is filled with some suitable insulating material 13 such as sulphur which may be placed in the opening in the molten state, in a manner to be later referred to.

A metal screw eye 14 or similar attaching

device is provided as a means of support for the insulating receptacle containing the electrodes. The eye of the attaching means 14 loosely surrounds the receptacle in the groove between the corrugations 3 and 4 so that the receptacle may be used as a handle for the ready insertion of the threaded portion of the screw eye in any suitable support such as a window casing. At the same time the receptacle or insulator portion is freely swivelled in the eye of the mounting member 14 and thereby no torsional strain can be introduced between these two portions of the device either during the attachment of the wires or subsequent to such attachment.

Association of the mounting member 14 and insulating receptacles as just described in connection with the structure shown in Figs. 1 and 2, is permanent in character. In certain instances it may be desirable to provide an assembly of the mounting member and insulating receptacle which may be readily disconnected when desired, as in some instances it may be desirable to remove the mounting member and use the device without the same.

Fig. 3 illustrates a modification for this purpose in which the eye of the mounting member 14 engages the insulating member below the corrugation 3 around the portion 4^a of the insulating receptacle. In order to accommodate the eye of the supporting member 14 in either of the two positions the corrugated portion of the insulating receptacle is formed with the diameter of the same at 3^a and at 4^a. The mounting member 14 as shown in Fig. 3 is held in loose assemblage with the insulating receptacle by means of the washer 15 which in turn is held in place by the lower nut 12. If it is desired to disconnect the mounting member from the rest of the structure it is only necessary to remove the lower nuts 12 and remove the washer 15 after which the mounting member 14 may be removed.

Reference is next had to the method of manufacture of the protective device in order to assemble the component parts of the structure, and an apparatus of the form shown in Fig. 4 may be used to hold the parts in proper relationship for assembly although it is to be understood that the use of the specific apparatus here shown is not necessary and numerous other forms of apparatus may be used instead. As shown in Fig. 4 the protective device is assembled in inverted position upon a base or holder 16. The base is provided with a vertical hole 17 into which the electrode 6 is inserted, the hole 17 being of the proper depth to properly position the electrode with respect to the insulating member or receptacle 1 which is subsequently inserted in the enlarged conical concentric opening, which thereby centrally locates the electrode with respect to the opening 5. The

electrode 7 is then inserted with its inner end or head 9 resting directly in contact with the head 8 of the other electrode. A vertical movable member 18 having a recess 19 in its lower end is then depressed by the operator 70 against the spring 20 the member 18 being slidably mounted in the arm 21 which in turn is supported by the column 22. By this means the electrode 7 is also centered with respect to the insulating receptacle and is 75 maintained in axial alignment with respect to the other electrode 6.

While the electrodes and insulating receptacle are thus held in substantial assembled position, insulating material which is molten 80 while in a heated state such as sulphur, is poured into the central axial opening from a ladle 23. As soon as the central opening has been filled and has begun to solidify, member 18 may be allowed to return to its 85 upper position and the device may then be removed.

By the method of construction just described, an inherent formation of the gap between the electrodes 7 and 8 takes place, 90 upon the cooling and solidification of the insulating material 13.

While it is of course not necessary to a practice of the present invention to know the cause of the gap thus forming, the following 95 theory is advanced as a probable one. As the molten material is poured into the central opening it causes the electrodes of brass or other metal to become heated and expand therefore increasing their length slightly. 100 As the sulphur or other molten material begins to solidify this action will naturally take place at the top and bottom of the central opening, where the cooling effect is greatest, so that the electrodes are at first held rigid 105 with respect to the enclosing insulating medium at their outer extremities. A continued cooling of the insulating material 13 with its consequent solidification progressing toward the center will cause the electrodes to shrink 110 or to decrease their length as temperature conditions return to normal, thereby causing a separation or a gap to occur between the heads 8 and 9.

By a proper portioning of parts a suitable 115 gap may thus be formed. While not desiring to be limited to any kind of material for the various parts of the device, or to any size of structure, the invention may be readily practiced by those skilled in the art by using a porcelain insulating receptacle having central opening therein approximately 2 $\frac{1}{2}$ inches long and $\frac{1}{2}$ inch in diameter in which two electrodes of brass are inserted, the electrodes being approximately $\frac{7}{32}$ inch in diameter, the insulating material being sulphur heated to a sufficient degree to cause it to flow freely.

It is of course to be understood that the present invention may be carried out with 130

other materials and it is also pointed out that another advantage exists in the above described method of assembly, in that if the gap between the electrodes is not of the correct size the same may be readily adjusted before the insulating material has had time to completely solidify by suitable manipulation of the nuts 10 or 12.

In certain forms of protective devices for the purpose described, the functioning of the device is dependent upon other constructions than a gap between two electrodes. It is to be understood that the form of insulating receptacle and its supporting structure as described and claimed is equally applicable to these other forms of protective devices.

Various modifications of the device are shown in the drawings described in the specification will suggest themselves to those skilled in the art and are to be accordingly considered as coming within the scope of the present invention and the appended claims.

What I claim is:

1. A protective device comprising in combination, an insulating receptacle having a central opening therethrough, a pair of metallic electrodes located in axial alignment within said opening with a space between their ends and means comprising an insulating sleeve cast around said electrodes throughout the full length of said opening for holding said electrodes in fixed relationship.

2. A protective device comprising in combination, an insulating receptacle having a central opening therethrough, a pair of metallic electrodes located in axial alignment within said opening with a space between their ends and means comprising an unitary solidified insulating member for holding said electrodes in fixed relationship.

3. A protective device comprising in combination, an insulating receptacle having a central opening therethrough, a pair of metallic electrodes located in axial alignment within said opening with a space between their ends and means comprising an unitary solidified insulating member cast in place in said tubular opening for holding said electrodes in fixed relationship.

4. A protective device comprising in combination an integral insulating receptacle having a bottom portion of cylindrical corrugated form and a top portion of truncated conical form, the lower edge of which projects beyond the bottom corrugated portion thereof, spaced electrodes located with said receptacle and supporting means for said receptacle including an eye loosely associated with said corrugated bottom portion of said receptacle.

In testimony whereof, I affix my signature.
HARRY A. EATHERTON.
